UNITED STATES PATENT OFFICE.

CHARLES BREAKLEY MOORE, OF EVANSTON, ILLINOIS, ASSIGNOR, BY MESME ASSIGNMENTS, TO AMERICAN ARCH COMPANY, OF NEW YORK, N. Y., A CORPORATION OF NEW YORK.

ARCH FOR LOCOMOTIVE-FURNACES.

1,669,974.

Specification of Letters Patent. Patented Aug. 12, 1913.

Application filed July 12, 1903. Serial No. 443,914.

To all whom it may concern:

Be it known that I, CHARLES BREAKLEY Moore, a citizen of the United States, and resident of Evanston, Cook county, Illinois, have invented certain new, useful, and Improved Arches for Locomotive-Furnaces, of which the following is a full, clear, and exact description, such as will enable others skilled in the art to which it appertains to make and use the same.

My invention relates to improvements in locomotive boiler furnaces and has for its object the improvement of the form, construction and arrangement of refractory brick arches for and in locomotive boiler fire boxes of the kind which are equipped with arch supporting tubes.

Special objects and advantages of my invention will appear hereinafter.

My invention consists in the combination with a locomotive fire box, equipped with inclined arch supporting tubes, of an arch body composed of refractory bricks resting upon said tubes and approaching the side sheets of the fire box, and locking bricks or blocks extending between the edges of the arch body and respective side sheets of the fire box, said locking bricks serving to securely lock or hold the arch body against lateral movement upon the supporting tubes.

My invention will be more readily understood by reference to the accompanying drawings forming part of this specification, and in which,

Figure 1, is a vertical section of a locomotive fire box of the "narrow" type, containing a refractory front arch embodying my invention, the section being on the line X-X of Fig. 2. Fig. 2, is an irregular horizontal section on the line Y-Y of Fig. 1. Fig. 3, is a vertical section on the lines Z-Z of Figs. 1 and 2. Fig. 4, is a sectional detail, substantially on the line V-V of Fig. 1. Fig. 5, is a plan view of the arch as it appears in a fire box of the "wide" type. Fig. 6, is a perspective detail of one of the locking blocks or bricks.

As shown in the drawings the walls of a locomotive fire box are constituted by the flue sheet 2; the side sheets 3, 3; the rear sheet 4 and the crown sheet 5.

6 represents the grate.

The flues 7, extend forward from the upper part of the flue sheet 2. The fire box is inclosed by the boiler shell and forms there-

with the usual front, side and rear water legs 8", 8' and 8. The arch tubes 9 occupy inclined positions and extend from the lower part of the flue sheet 2, to the upper part of the rear sheet 4. The water from the front 60 water leg 8" flows through the tubes to the rear water leg 8 and prevents the burning out of the tubes.

Fire boxes of different types and sizes require arch tubes of different forms and 65 inclinations, also different numbers thereof; but they are essentially the same, and perform the same functions in all cases. Locomotive fire boxes are of two principal types; the "wide" type and the "narrow" type. 70 Fire boxes of the "wide" type, as shown in Fig. 5, are characterized by side sheets which are substantially vertical or which flare outwardly at the bottom, the grate, generally, being of practically the same 75 width as the top of the fire box. "Narrow" fire boxes as shown in Figs. 1 to 4, are characterized by side sheets which curve or flare inwardly at the bottom, their grates being narrower.

Notwithstanding the different shapes, to avoid confusion, I have applied the same reference numerals to corresponding parts throughout the drawings of both the "narrow" and the "wide" fire boxes.

My invention as herein represented is readily adaptable to all types and sizes of locomotive fire boxes and overcomes the difficulties met with, and the objections hitherto urged against the use of, arch tubes and 90 refractory arches in locomotives, including such as are common to all types as well as the objections and difficulties that are individually characteristic thereof.

The arch rests upon the arch tubes and is 95 composed of a number of refractory bricks; these usually take their dimensions from the fuel door of the fire box, through which they must be passed if the removal of the grate is to be avoided. In fact larger bricks 100 are too heavy for convenient handling and it is desirable that they be as small as here indicated.

In carrying out the invention I employ as many arch tubes as may be required to suit 105 the dimensions of the bricks and the dimensions of the fire box. In placing the arch tubes in the fire box I space them to correspond with the transverse width of the arch bricks and I leave, between the outermost 110

tubes and the side sheets, sufficient space to permit easy access to the side sheets and the stay bolts, which require frequent inspection and repair.

5 My novel arch comprises a substantially rectangular body portion or arch proper made up of a plurality of refractory bricks A, fitted together as shown, and resting upon the arch tubes 9. The arch body may 10 comprise one, two, three or more longitudinal rows of these bricks A, according to the dimensions of the fire box and the spacing of the arch tubes. The arches herein shown are so-called solid arches, being made up of 15 solid or imperforate brick, but I desire that it shall be understood that my invention is also applicable in the construction of so-called hollow arches particularly such as embody the principles of the Wade and 20 Nicholson inventions.

As shown in the drawings, small refractory bricks or blocks B, are used at the lower end of the arch to hold the same away from the flue sheets 2. These bricks are provided 25 with grooves or channels b in their undersides to fit the tubes 9, and they are provided with relatively inclined ends b' and b'' to engage the flue sheet and the lower bricks A of the arch, respectively. The arch 30 presses upon the blocks B, and with the tubes 9 serves to effectively lock the blocks B, against displacement by the vibration of the locomotive. These blocks B are particularly adapted for use with solid arches and 35 by use thereof two special advantages are secured, i. e. they obviate the necessity for shaping or forming the lower arch bricks to fit the bent ends of the arch tubes and the relatively angular flue sheet and also 40 provide cinder discharge openings at the lower end of the arch adjacent to the flue sheet. For securing the arch body against lateral movement on the arch tubes, I employ a plurality of locking bricks or blocks 45 D. These I form after the manner of wedges and arrange them between the edges of the arch body and the side sheets of the fire box, in which position they constitute self-tightening wedges, struts or blocks and 50 securely lock the arch bricks A, between the sides of the fire box and upon the arch tubes. As shown in both Figs. 2 and 5, each side locking block rests upon or engages the ends of two of the body bricks A, and the locking blocks at one side of the arch are directly opposite those at the other side thereof. In "wide" or straight sided fire boxes (Fig. 5) and in the lower parts of "narrow" fire boxes, (Fig. 2) I find it possible 55 to use locking blocks D, of uniform dimensions. If desired these blocks D may be, and they usually are, identical with the blocks B, one mold being used in making them. The blocks B, however, are inverted with 60 respect to the blocks D.

The upper part of a "narrow" fire box is wider than the lower part, and for securing the upper bricks of the arch body, I employ wedge blocks or struts D', which are longer and preferably wider than the blocks B and D. As shown in the drawings, the ends of the body bricks A, may be notched to receive and hold the locking blocks D, although there is slight danger of the dislodgment of the wedge blocks after they have been placed in position. The lower ends of the wedge blocks rest upon the edges of the arch body and their upper ends lean and wedge against the side sheets. The shorter blocks D usually occupy inclined positions as shown in Fig. 3. The ends of the blocks D, are relatively inclined as in the case of the blocks B, and the longer sides of the blocks D are placed uppermost, so that the blocks constitute true wedges between the arch and the side sheets. To provide proper bearings for the lower or inner ends of the locking blocks, I prefer to bevel the edges a of the arch brick, as shown in the drawings, but if desired the beveled surfaces on the bricks may be restricted to correspond to the ends of the locking blocks. The bricks A, are however, more readily interchangeable when their ends are fully beveled as herein shown. The bases or inner ends of the locking blocks are preferably wider than the outer ends thereof and said outer ends are formed to minimize the area of engagement between the locking bricks and the side sheets. In making the bricks D', I prefer to provide them with ends d'', that are pointed in order that they may be interchangeable. The manner in which the bricks D' engage the side sheets is clearly shown in Fig. 3.

A special advantage of my novel arch lies in the fact that while its members serve to securely hold it between the side sheets of the fire box, the small locking blocks may be readily knocked out when it is necessary to repair the arch or the side sheets of the furnace. It is obvious also that the locking blocks secure the arch in place without covering the side sheets to such extent as to prevent the uniform heating and cooling thereof or inspection of the stay bolt. These locking blocks also possess the advantage of readily accommodating the arch to fire boxes of varying widths and to such as may have corrugated, warped or patched side sheets.

As various modifications of my invention will readily suggest themselves to one skilled in the art, I do not confine the invention to the specific shape, structure or arrangement of bricks herein shown and described.

Having thus described my invention, I claim as new and desire to secure by Letters Patent:—

1. A locomotive boiler furnace, in combi-

nation with a group of arch tubes of less width than said furnace, a refractory arch spaced from the flue sheet and comprising a body portion laterally co-extensive with said 5 group of arch tubes and provided with upwardly and inwardly inclined beveled edges and edge projections, and refractory locking blocks acting as wedges between said body portion and the side sheets, having their 10 outer ends engaged with respective side sheets and their inner ends formed to fit respective beveled edges of the arch body and held by the projections thereon, substantially as described.

15 2. A locomotive boiler furnace containing a group of arch tubes, in combination with a refractory arch resting on said tubes and of less width than the furnace, wedge shaped blocks upon said tubes between the flue 20 sheet of the furnace and the lower end of the arch, and other, identical wedge blocks engaged with the sides of the furnace and wedging the arch between said sides, substantially as described.

25 3. A locking brick or block for locomotive

furnace arches, having relatively inclined ends and relatively inclined sides and in its long side provided with a longitudinal groove to fit an arch tube, said block being longitudinally tapered and of greatest area at its 30 end which is adapted to be placed against the arch, substantially as described.

4. A locomotive boiler furnace containing a group of arch tubes, in combination with a refractory arch resting on said tubes and 35 of less width than the furnace and a plurality of wedge bricks spacing the bottom of said arch from the flue sheets, and relatively inverted, identical wedge bricks wedging said arch between the sides of the 40 furnace, respectively, substantially as described.

In testimony whereof, I have hereunto set my hand, this 23rd day of June, 1908, in the presence of two subscribing witnesses.
